US0D1002839S

(12) **United States Design Patent** (10) **Patent No.:** **US D1,002,839 S**
(45) **Date of Patent:** **** Oct. 24, 2023**

(54) **SANITARY PAD**

(71) Applicant: **Angelica M. Anousis**, Quincy, MA (US)

(72) Inventor: **Angelica M. Anousis**, Quincy, MA (US)

(**) Term: **15 Years**

(21) Appl. No.: **29/841,991**

(22) Filed: **Jun. 9, 2022**

Related U.S. Application Data

(62) Division of application No. 29/732,445, filed on Apr. 24, 2020, now Pat. No. Des. 958,335.

(57) **CLAIM**

The ornamental design for a sanitary pad, as shown and described.

DESCRIPTION

FIG. 1 is a perspective view of a portion thereof;

FIG. 2 is a top plan view of a portion thereof;

FIG. 3 is a rear end view of a portion thereof;

FIG. 4 is a front end view of a portion thereof;

FIG. 5 is a right side view of a portion thereof;

FIG. 6 is a left side view of a portion thereof; and,

FIG. 7 is a bottom plan view of a portion thereof.

The broken lines shown in FIGS. 1-7 illustrate portions of the sanitary pad that form no part of the claimed design.
